UNITED STATES PATENT OFFICE

FRANK PARDEE, JR., OF HAZLETON, PENNSYLVANIA, ASSIGNOR TO ANTHRACITE SEPARATOR COMPANY, OF HAZLETON, PENNSYLVANIA, A CORPORATION OF PENNSYLVANIA.

APPARATUS FOR LOWERING COAL AND THE LIKE

Application filed May 28, 1930. Serial No. 456,365.

This invention relates to improvements in apparatus for handling coal and like materials and aims to provide flexible or extensible means which can be retracted as the material being lowered piles up or accumulates. While not limited thereto the apparatus shown is well adapted for lowering coal from a coal pocket or conveyor to a railway car or from a retail coal bin to a delivery truck. The device is particularly adapted to gently lower sized material with a minimum production of fines. This is of importance in coal handling because so-called fines have very little sale value and commercial grades of sized coal contaminated with a mixture of fines is regarded by the trade and also by coal consumers as a somewhat inferior product and therefore does not command such a good price as relatively clean coal stock unmixed with any appreciable amount of fines or small pieces broken from the lumps.

Various forms of spiral chutes and fixed structures having oppositely inclined runway portions have heretofore been used for the lowering of coal. But, these prior devices are not well suited for transferring the coal from a coal pocket or conveyor to a railway car or from a retail coal bin to a delivery truck because of the inability to conveniently vary the point of ultimate delivery as the pile grows.

The present invention aims to provide extensible apparatus which can be readily retracted as the lowered material piles up in a railway car or other conveyor. The apparatus is also adapted to be easily applied to existing coal storage pockets, conveyors or retail bins with very little or no material alteration to existing parts thereof.

The invention will be fully apparent from the following specification when read in connection with the accompanying drawings and will be pointed out with particularity in the appended claims.

In the drawings:

Fig. 1 is an elevation showing a portion of a coal pocket having delivery apparatus applied thereto embodying the invention;

Fig. 2 is an enlarged vertical sectional view illustrating details of construction;

Fig. 3 is a cross sectional view illustrating an embodiment of the invention wherein the extensible chute is suspended from a guide track in turn supported on a carriage which moves relatively to a storage bin;

Fig. 4 is a section on line 4—4 of Fig. 3;

Fig. 5 is a detail view illustrating a portion of the flexible or extensible chute;

Fig. 6 is a section on line 6—6 of Figs. 2 and 5;

Fig. 7 is a detail view of a plate such as is used interchangeably for forming the end members of the separate sections of the flexible chute;

Fig. 8 is a detail section illustrating a structural modification;

Fig. 9 is a view illustrating a modified form of flexible chute;

Fig. 10 is a cross section on line 10—10 of Fig. 9;

Figs. 11 to 17 inclusive are views illustrating modified flexible chute constructions, Fig. 13 being an elevation from the left of Fig. 12;

Fig. 18 is a somewhat diagrammatic view illustrating a modification of the construction shown in Fig. 3 wherein a counter-weight and a guide track are provided to counterbalance the weight of the extensible chute;

Fig. 19 is a detail elevation and Fig. 20 an enlarged section thereof illustrating a modification;

Fig. 21 is a diagram of a further modification;

Referring in detail first to Figs. 1 to 6 inclusive of the drawings, 10 represents a coal pocket having the usual inclined floor 12 and an outlet chute 14 provided with a suitable control gate 16. Mounted in juxtaposition to the outlet chute of the coal pocket there is a flexible or extensible chute indicated as a whole at 18. This chute comprises a multiplicity of sections 20 which are pivotally or flexibly connected to one another so that they may be successively brought to position opposite the outlet chute of the coal pocket so as to receive material therefrom. The sections carry supporting projections which are adapted to engage a supporting member 100

mounted in juxtaposition to the coal pocket. In the embodiment illustrated, the supporting projections are in the form of rollers 22 carried by pivot pins 24 which pivotally connect the adjacent sections 20 with one another. These rollers ride in a groove 26 formed in a guide track or supporting member 28 which is secured to the coal pocket by suitable brackets as shown in Fig. 1. Where the coal pocket has an inclined bottom as shown, the track can conveniently be disposed on an incline substantially parallel with the bottom and its lower end can be curved around as indicated at 30 so as to guide the sections 20 into the proper position opposite the discharge orifice of the outlet chute 14. The flexible chute is connected at its upper extremity by means of a cable 32 with a power actuated device such as an electric hoist 34 or the like.

Each section 20 of the flexible chute includes a pair of oppositely inclined runway portions 36 and 38 over which the coal or other material to be lowered is adapted to travel in a zig-zag or sinuous path so as to lessen its rapidity of flow under the influence of gravity. As clearly shown in Fig. 2, the runway portions 38 at the right side of the sections 20 are provided with extensions or upright portions 40. These serve to prevent the oncoming material, from the outlet chute 14, from overflowing. In operation of the apparatus shown in Figs. 1 to 6 inclusive an empty railway car such as shown diagrammatically in Fig. 1 at 42 will be positioned below the chute 14. The flexible chute will be lowered so that the bottom-most section barely clears the floor of the car. The gate of the discharge chute 14 will then be opened and the coal permitted to gradually descend in a zig-zag path over the oppositely inclined runway portions 38 of the several sections 20. As the pile builds up in the car the hoist will be operated at intervals so as to periodically raise the flexible chute and thus successively bring different sections opposite the discharge outlet of the coal pocket. In this way, the pile can be gradually built up in the car without permitting the lumps of coal to drop any such great distance as would be likely to cause breakage or production of unsaleable fines. The car of course can be moved longitudinally at different intervals to stack the coal along different parts of its length. Thus by manipulation of the flexible chute a uniform loading of the car can be easily secured.

In the loading of delivery trucks in retail coal yards a somewhat similar arrangement can be readily supplied. However, retail dealers may not require a separate loading device for each outlet chute of the bin. I, therefore, propose to provide an arrangement whereby a single flexible lowering chute may serve a plurality of discharge chutes from the retail bin. Such an arrangement

is illustrated in Figs. 3 and 4. This bin 10^a is provided with a plurality of fixed discharge chutes 14^a. To serve these several chutes, I provide a single flexible discharge chute 18^a which is carried by a guide track 28^a. This guide track is suspended from suitable brackets depending from a carriage or traveller 44 having supporting rollers 46 which ride in channel guides 48 secured to the bin. As thus arranged it will be clear that the flexible delivery chute 18^a can be positioned opposite any selected one of several discharge chutes 14^a merely by moving the carriage along the tracks 48. In the arrangement of Fig. 3, which is particularly adapted for retail coal yards, the flexible chute is preferably raised and lowered manually chiefly to save expense of installation of electric hoists such as used in the larger coal pockets which handle a greater volume of material. It, therefore, becomes desirable in the arrangement of Fig. 3 to provide counter-balancing means to minimize the labor involved in manipulating the extensible or flexible chute. For raising and lowering the chute, I may provide in the construction of Fig. 3 a common type of differential or so-called geared block 50 which is suitably supported from the carriage 44. This block is connected by means of a cable 52 to the uppermost section 20^a of the flexible chute as shown.

For counter-balancing the weight of the parts, I provide a long extensible spring 54, one end of which is connected to the uppermost section 20^a of the chute, the other end of the spring being secured to a spring anchorage 56 extending outwardly from the carriage 44. With this arrangement, it will be understood that by pulling the hand chain 58, of the differential block in the proper direction, the sections of the flexible chute can be retracted, the spring 54 serving as a counter-balance. If desired, in some cases the geared block may be entirely dispensed with, the spring being strong enough to pull back the sections 20^a when the operator exerts a slight lifting effort on the vertically disposed chutes.

Instead of using the spring counter-balancing means of Fig. 3, I may employ a weight such as shown at 60 in Fig. 18, this weight being of circular form and adapted to roll on a track having a vertical portion 62 and an inclined or curved portion 64. The weight will be connected by a cable 66 which is secured at 68 to another cable 70 connected at 72 to the end section of the flexible conveyor. The cables 66 and 70 pass over a suitable guide sheave 74. By exerting a pull in the direction of the arrowhead P, it will be understood that the lowermost section of the flexible conveyor will be elevated. At the same time, the counter weight 60 will descend along the vertical part 62 of the guide track.

After a number of the sections of the flexible conveyor have been lifted to horizontal position, where they are supported by a guide track like that shown at 28 in Fig. 3, the counter-weight will reach the dotted position shown in Fig. 18 on the inclined part of the track so as to exert a gradually decreasing pull on the conveyor as the successive sections thereof come into horizontal position on the guide track 28.

The design and construction of the sections of the flexible conveyor may be varied to suit particular conditions or to simplify the production of the device from a manufacturing standpoint. Various forms of conveyor sections are illustrated in detail in Figs. 5 to 17 inclusive.

In the construction of Figs. 5 to 7, each conveyor section 20 includes end members 20 made from a plurality of duplicate punchings or plates 76 such as shown in Fig. 7. The plate 76 when turned over will appear as shown at 78 in Fig. 5. The two plates indicated at 76 and 78 in Fig. 5 are riveted, welded or otherwise secured to one another as shown in Fig. 6, the rivets 80 being shown as an illustration of one form of fastening. These two plates 76 and 78 jointly constitute a single end member for the conveyor section. The inclined runway portion 36 has a flange 37 which is adapted to be riveted or otherwise secured to the plate 76. The inclined runway member 38 has a similar flange 39 which is adapted to be riveted or otherwise secured to the plate 78. The plates 76 and 78 are perforated at 82 for the reception of the pins 24 which connect the adjacent sections 20 with one another. As thus arranged, it will be understood that from the standpoint of manufacture a great number of identical or duplicate plates 76 and 78 can be punched out and secured to one another as shown in Fig. 5 so as to cheaply form the chute section 20. In the modification of Fig. 8 the plate 76 may be formed with a flange 77 to receive the runway portion 36a. With such flanged arrangement, a duplicate formation of parts can also be followed, it merely being necessary to bend the flanges 77 in opposite directions to form rights and lefts.

Fig. 9 illustrates a construction wherein a flexible chute section 20b comprises a pair of end members 84 each formed of one single piece and having oppositely inclined runway portions 86 and 88 secured thereto, these portions having flanges 87 and 89 which are riveted or otherwise secured to the end members 84 as shown.

In the modification of Fig. 11, I show end members 90 flexibly connected to one another by links 92, the end members carrying oppositely inclined runway portions 94 and 96.

Figs. 12 and 13 show a modification in which oppositely inclined runways 98 and 100 are formed integrally with end members

99 and 101, the end members being flexibly connected by pivots 102. In this arrangement every alternate pivot 102 will preferably carry a roller 104 for coaction with a suitable supporting guide track.

A flexible chute section shown in Fig. 14 includes a plurality of substantially rectangular end plates 106 having oppositely inclined runway portions 108 and 110, the several end plates being connected by pivot pins 112 adapted to carry rollers as shown in the other figures. Fig. 15 shows an arrangement quite similar to Fig. 14 except that the runway portions 110a are curved inwardly and downwardly.

Fig. 16 shows a modification in which a transversely curved inclined runway portion 114 is carried by flanges 116 formed at the lower extremities of end members 118.

In the modification of Fig. 17, the end members 120 of the conveyor section are pivotally connected by pins 122. Each end member 120 carries at the left an inclined runway portion 124. At the right, each end section carries a substantially angle-shaped member 126 the portion 128 of which forms a runway and the portion 130 of which serves to prevent the material traveling in the flexible section from overflowing.

For preventing flexible sections of the chute from catching or interfering with the fixed feed chute 14, I preferably provide a guide chute or deflector 132 which extends downwardly and away from the flexible chute as shown in Figs. 1 and 2. This deflector 100 may be formed of bars or a similar plate bent to form. In either case they are bolted to any fixed structure. For example, it may be secured directly to the underside of the outlet chute 14 of the coal pocket as shown.

It is desirable to restrict the flow of coal or other material at the outlet end of the lowering chute. This restricted flow can be secured by so forming one or more sections at the lower end of the separator that the flow area is less than that of other sections. As indicated in Fig. 13, this reduction of area may be secured by fastening fillers 134 to one or more of the lowermost sections of the flexible chute. A similar result could be secured by gradually decreasing the width of some of the sections. Such a restriction of the cross sectional area of the space through which the coal flows at the delivery end of the chute causes the chute to fill up. And the material travels in a substantially continuous unbroken stream. This is desirable because it prevents separate pieces dropping one at a time from one runway section to the other.

In the modification illustrated in Figs. 19 and 20, the runway sections are formed of side plates 134 of the shape shown. These carry angle brackets 136 which support inclined runway members 138 which are bent 130

over at 140 to form transversely extending stiffening flanges. These flanges are also adapted to guide the moving stream in its downward flow and to prevent spillage. Opposite the runway portions 138, there are complementary runway members 142 having upward extensions 144 substantially the same as those shown at 40 in Fig. 2. The runway member 142 is carried by a flange 146 bent inwardly from the side plate 134, the parts being riveted or otherwise secured.

Referring to Fig. 21, the length of the inclined runway portions may be varied by providing bent over portions of different lengths as indicated in dotted lines at 148, 150 and 152. In practice, when the lower end of the runway is bent over at point 148, the chute will be suitable for handling egg size coal, when bent over at 150, it will be suitable for stove size coal. For nut coal, the length of the runway will be slightly greater, the flange being bent over as indicated at 152. For handling pea coal, or buckwheat, the runway will terminate at 154. This arrangement permits the use of the same pattern of runway for all sizes of coal from approximately four inches down to buckwheat size. The transverse width of the runway as the distance between the side plates of the conveyor sections can of course be varied to suit the different sizes of the coal handled or to suit the rate at which it is desired to discharge the coal. Flanging over the lower ends of the runway at the points indicated at 148, 150 and 152 prevents spillage of coal over the point 156 of the next lower runway section. Such spillage is of course to be prevented in order to avoid the undesirable breakage.

While I have described quite specifically various details of the embodiments of the invention herein illustrated it is not to be construed that I am limited thereto since various changes and modifications may be made by those skilled in the art without departing from the invention as defined in the appended claims.

What I claim is:

1. An apparatus for lowering coal and similar material comprising a bin or pocket having an outlet and a flexible chute including a series of runway carrying sections flexibly connected with one another and adapted to be successively positioned adjacent said outlet, and a guide for supporting the sections shaped to change the direction of travel of said sections with relation to said outlet, said sections having means which ride on said guide.

2. An apparatus for lowering coal and similar material comprising a bin pocket having an outlet and a flexible chute including a series of runway carrying sections pivotally connected directly with one another and adapted to be successively positioned adjacent said outlet, a guide track for said sec-

tions carried by the bin, and means for pulling the sections along said track, anti-friction supports carried by said sections adapted to be guided by said track.

3. An apparatus for lowering coal and similar material comprising a bin or pocket having an outlet and a flexible chute including a series of runway carrying sections flexibly connected with one another and adapted to be successively positioned adjacent said outlet, each section carrying a supporting projection and a supporting member for coaction with the supporting projection of the several sections.

4. An apparatus for lowering coal and similar material comprising a bin or pocket having an outlet and a flexible chute including a series of runway carrying sections flexibly connected with one another and adapted to be successively positioned adjacent said outlet, each section carrying a supporting roller and a guide track for coaction with said rollers.

5. An apparatus for lowering coal and similar material comprising a bin or pocket having an outlet and a flexible chute including a series of runway carrying sections hingedly connected with one another supporting members on said sections and means coacting with said members for guiding said sections in juxtaposition to the outlet of said bin.

6. An apparatus for lowering coal and similar material comprising a bin or pocket having an outlet and a flexible chute including a series of sections adapted to receive material from said outlet, means for flexibly connecting the several sections, means for movably supporting the sections adjacent the bin, means for moving said sections and means for counterbalancing the weight of the sections to facilitate their movement.

7. An apparatus for lowering coal and similar material including a flexible chute comprising a plurality of separate sections, each section having a pair of end members, runway members bridging the space between said end members, pivot pins connecting the end members of adjacent sections, supporting rollers carried by said pivot pins and a guide track along which the rollers travel.

8. Apparatus for lowering coal and similar material comprising a flexible chute including a series of runway carrying sections connected with one another with freedom for relative angular movement and a track adapted to alter the angular relationship between one or more sections of the chute, each of said sections having means for engagement with said track.

9. Apparatus for lowering coal and similar material comprising a flexible chute including a series of runway carrying sections hingedly connected with one another, a supporting member, and means carried by said

sections adapted to be guided by said supporting member.

10. Apparatus for lowering coal and similar material comprising a flexible chute including a series of runway carrying sections hingedly connected with one another, a supporting track having one portion disposed at an angle to another portion thereof and means carried by said sections adapted to be 10 guided by said track.

11. Apparatus for lowering coal and similar material comprising a flexible chute including a series of runway carrying sections hingedly connected with one another, a supporting track and means carried by said sections adapted to be guided by and travel 15 along said track, and means for pulling successive sections into supporting engagement with the track.

20 12. Apparatus for lowering coal and similar material comprising a flexible chute including a series of runway carrying sections flexibly connected with one another, a guiding and supporting track, and rollers carried 25 by said sections adapted to successively coat with the supporting track.

In witness whereof, I have hereunto signed my name.

FRANK PARDEE, JR.
